[57] ABSTRACT

A spray nozzle having an internal bore for spray liquid and a transverse deflector plate disposed in the path of the liquid jet from the nozzle. The deflector plate is mounted on a rod extending axially through the bore of the nozzle and rigidly mounted by a spider having radial legs and a peripheral ring from which the legs extend both radially and axially. The outer edges of the legs closely fit the inner bore of the nozzle for centering the rod and the clamping of the ring secures the rod in place.

DEFLECTOR SUPPORT FOR SPRAY NOZZLE

This invention relates to spray nozzles and has for an object to provide a 360° spray nozzle having novel and improved characteristics.

A feature of the invention is the provision of means for maintaining a uniform spray pattern around the entire 360° of the spray. The invention is applied to a nozzle of the type including an element having a central bore adapted to eject a jet of liquid axially and a radially curved concentric deflector plate disposed in the path of the jet for deflecting the jet into a radial spray extending around its entire periphery. The deflector plate is supported on a rod extending axially through the bore of the nozzle.

In nozzles of this type it is essential to center the deflector plate accurately in order to obtain uniformity of spray pattern. At the same time the centering device must be readily removable for replacement and service.

An object of this invention is to provide novel and improved centering means for a supporting rod for the deflector plate in nozzles of the above type.

In one embodiment the rod is mounted in a spider having a set of radial legs carried by a peripheral ring. The ring is adapted to be clamped against the end of the nozzle element by a coupling member. The legs of the spider are of a width to extend axially beyond the ring with their outer edges machined to fit accurately in the bore of the nozzle. The legs thus serve to center the rod and deflector plate and the outer ring serves to clamp the same securely in place in centered position.

The nature of the invention will be better understood from the following description, taken in connection with the accompanying drawing in which a specific embodiment has been set forth for purposes of illustration.

In the drawing:

FIG. 1 is an axial section through a nozzle embodying the invention;

FIG. 2 is a detail section taken on the line 2—2 of FIG. 1 showing the construction of the supporting spider; and

FIG. 3 is an axial section similar to FIG. 1 illustrating a further embodiment of the invention.

Referring to the drawing more in detail, the device is shown as embodying a nozzle element 10 of generally standard construction having a rim 11 at its leading end and an axial bore having a tapered wall 12 at its leading end and a cylindrical wall 13 at its trailing end from which the liquid is discharged in the form of a jet. At its base the element 10 has an externally threaded coupling portion 14 and an outer surface 15 tapering to the discharge end. An axial rod 20 extends through the bore of the element 10 and is supported by a spider having a series of radial legs 21 and an integral peripheral ring 22. The ring 22 is machined to fit accurately against the rim 11 of the element 10 and is of a thickness to be clamped by a coupling member 25 between the rim 11 and the end of a supply pipe 26. The pipe 26 carries a flange 27 to be engaged by the coupling member 25 which is threaded onto the threaded portion 14 of the element 10.

The radial legs 21 extend axially beyond the ring 22 and have outer edges 28 which are machined to fit accurately against the tapered wall 12 of the element 10 so as to center the spider and the rod 20 when inserted in the bore of the element and to be clamped rigidly in place when so centered by means of the coupling mem-

ber 25. The surface of the ring 22 which engages the rim 11 of the nozzle element is accurately machined for holding the rod 20 and deflector disc 30 in rigid axial alignment with the nozzle element 10.

The rod 20 carries at its trailing end a deflector disc 30 having a symmetrically curved forward surface 31 adapted to deflect the liquid of the jet radially in all directions to form a 360° spray pattern. The accurate centering of this deflector ensures a uniform spray pattern around the entire periphery of the nozzle. The deflector disc 30 is shown as threaded onto the rod 20 and may be fixed in adjusted position by a set screw 33. The rearward surface 34 of the deflector disc 30 is shown as convex to improve the air flow thereover if used to pass an air stream through the spray zone as in a gas washing apparatus. The nozzle is, however, adapted for general use where a 360° spray pattern is required.

In operation the rod 20 and the deflector plate 30 are accurately centered and positioned during assembly by the contact in surfaces of the outer portions 28 of the legs 21 and the tapered surface 12 of the bore in the element 10 and are securely and rigidly clamped by the ring 22 against the rim 11 of the nozzle element. The parts may be removed and replaced in a similar manner and, when so clamped in position, the deflector disc 30 is accurately centered without further manual adjustment.

The embodiment of FIG. 3 is similar to that above described and corresponding parts have been given the same reference numbers with the suffix *a*. In this embodiment the outer edges 28a of the spider legs 21a are shown as seated against the corresponding tapered bore 12a of the nozzle element 10a with the retaining ring 22a spaced from the end 11a of the nozzle element 10a. A coupling member 40 is threaded onto the leading end of the nozzle element 10a and has an inner peripheral flange 41 which engages the retaining ring 22a and exerts pressure for seating and centering the spider in the bore 12a of the nozzle element. The surface of the flange 41 which engages the ring 22a is accurately machined to hold the rod 20a and disc 30a in accurate axial alignment with the nozzle element 10a. The supply pipe 26a is threaded into the coupling member 40.

The arrangement and operation are similar to that of FIGS. 1 and 2 except that the tapered seating of the spider legs 21a permits the nozzle to be adjusted for wear of the parts and ensures a rigid support for the rod 20a and deflector, not shown.

What is claimed is:

1. In a spray nozzle having an axial bore for ejecting a jet of liquid, a transverse deflector plate disposed in the path of said jet and a supporting rod for said plate extending axially through said bore, a supporting spider for said rod having a set of radial legs and a peripheral ring carrying said legs, said nozzle having an end rim against which said ring is adapted to be seated and said legs having outer end portions shaped to fit accurately in said bore of said nozzle for centering the spider and rod.

2. A nozzle as set forth in claim 1 in which said bore is tapered and the outer end portions of said legs are correspondingly tapered.

3. A nozzle as set forth in claim 1 in which said legs have a greater axial width than said ring whereby said legs extend beyond said ring inwardly and axially to provide said outer surface for centering.

4. A nozzle as set forth in claim 1 including a coupling member having means to clamp said ring against said rim of said nozzle.
